UNITED STATES PATENT OFFICE

WILLIAM JOSEPH PERRY, OF SHOOTER'S HILL, LONDON, ENGLAND, ASSIGNOR TO THE INDIA RUBBER GUTTA PERCHA & TELEGRAPH WORKS COMPANY LIMITED, OF LONDON, ENGLAND

DESIGN FOR A GOLF BALL

Application filed January 3, 1930. Serial No. 34,013. Term of patent 14 years.

To all whom it may concern:

Be it known that I, WILLIAM JOSEPH PERRY, a subject of the King of England, residing at Milestone, Shooter's Hill, London, S. E., England, have invented a new, original, and ornamental Design for a Golf Ball, of which the following is a specification, reference being had to the accompanying drawing, forming part thereof.

The figures are perspective views of the golf ball illustrating my new design.

I claim:

The ornamental design for a golf ball as shown.

WILLIAM JOSEPH PERRY.
